B. L. BLAIR.

BALL PROJECTOR.

APPLICATION FILED JAN. 20, 1919. RENEWED JULY 9, 1921.

1,419,445.

Patented June 13, 1922.

INVENTOR

Benjamin L. Blair,
By Frank W. Moore,
ATTORNEY.

UNITED STATES PATENT OFFICE.

BENJAMIN L. BLAIR, OF INDIANAPOLIS, INDIANA.

BALL PROJECTOR.

1,419,445.

Specification of Letters Patent. Patented June 13, 1922.

Application filed January 20, 1919, Serial No. 271,972. Renewed July 9, 1921. Serial No. 483,611.

To all whom it may concern:

Be it known that I, BENJAMIN L. BLAIR, a citizen of the United States, residing at Indianapolis, in the county of Marion and 5 State of Indiana, have invented certain new and useful Improvements in Ball Projectors, of which the following is a specification.

This invention relates to certain means for controlling and directing the discharge of 10 compressed air against the periphery of a ball for effecting its discharge from an air gun, such as is shown and described in my co-pending application for air gun, filed April 13, 1917, Serial No. 161,790.

15 One of the objects of the present invention is to provide means by which compressed air can be discharged against a predetermined localized peripheral area and radially of the axis of a ball to cause rotational travel in 20 the desired direction to be imparted to the ball.

A further object of the invention consists 25 in the provision of certain means by which compressed air discharged against the periphery of a ball can be varied, as necessity therefor may dictate.

30 I accomplish the above objects of the invention by means of the construction illustrated in the accompanying drawings, forming a part hereof, in which—

Figure 1 is a fragmentary detail view showing the air discharge gun in side elevation with the ball chute in section. Fig. 2 is a fragmentary detail view partly in front 35 elevation, the remaining part of the air discharge device being broken away, on a considerably enlarged scale. Fig. 3 is a fragmentary detail vertical sectional view on the line 3—3 in Fig. 2.

40 Referring to the drawings, 10 represents a cylinder for confining the compressed air, and said cylinder is provided with a port 11 through which the compressed air is discharged. Air passing out through discharge 45 opening 11 is controlled by means of a suitable valve 12, the latter being actuated by certain mechanism described in the above mentioned co-pending application. Port 11 communicates with a collar 14 which is 50 threaded into a hub 15 formed integrally with cylinder 10, and said collar is provided on its free external surface with an annular shoulder 16. Shoulder 16 engages an annular recess 17 in the adjacent face of a 55 revoluble air discharge head 18, and by means of a plate 50 secured to the rear sur-

face of head 18, by means of the screws 20, head 18 is prevented from being accidentally displaced from collar 14. The above described connection between collar 14 and head 18 permits the latter to be rotated freely around the former, the object of which will be hereinafter described. The passageway through collar 14 communicates not only with port 11 in cylinder 10, but also with 60 an air discharge passageway 22 in head 18. Passageway 22 while entering at the axis of head 18 is curved so as to bring its discharge end 19 near the edge of the margin of the face of head 18, so that the air discharged 65 from passageway 22 will be directed against the surface and at one side of the axis of the ball. Air discharged against the surface of a ball with passageway 22 occupying the position shown in Fig. 3 will cause rotational 70 movement to be imparted to the ball in a direction as indicated by the arrow in said Fig. 3, so that the theoretical axis of the ball will be horizontal during its flight. As cylinder 10 and remaining mechanism of 75 the air gun have a combined length to place the operator a considerable distance back of head 18, I provide means by which head 18 may be easily rotated from the operator's stand. This is accomplished by providing 80 the annular shoulder 25 of head 18 with a plurality of annular channels 26 adapted to receive an operating-cord 27. Cord 27 is passed around head 18 a number of times, and the ends of said cord pass back to the 85 operator. When a pull is exerted on one end of cord 27 head 18 is rotated in one direction, while a pull exerted on the other end of cord 27 will rotate head 18 in the opposite direction, thereby moving the discharge end 90 19 of passageway 22 into the desired position 95 relatively to the ball. The front face of head 18 is cut on a concave arc corresponding to the arc of the periphery of the ball, insuring as large an area of peripheral contact surface as possible between said ball and head. If the area of the discharge end 19 of passageway 22 remained constant, a uniform volume of air would constantly be 100 discharged against the surface of the ball under a given pressure, thereby imparting a uniform velocity of travel to the ball. This is not the result desired, for the reason that when using the present device for 105 throwing base-balls during batting exercises the batters would soon become familiar with the uniformity of travel of the ball and the 110

amount of break or curve it would possess, thereby enabling him to readily and successfully bat each ball thrown to him. To add uncertainty and doubt as to the course the 5 ball will travel, the direction in which it will break, and its speed of travel, is accomplished by rotating head 18 about collar 14 and by reducing and increasing the volume of air discharged against the periphery of 10 the ball. As I have heretofore explained that by rotating the head 18 for intermittently discharging the air at different points against the surface of the ball for changing the direction of its rotational movement, the 15 increase and decrease in pressure of the air discharged against the surface of the ball will not only vary its axial movement but also its velocity throughout its course of travel. This is effected by means of a wedge 20 shape plunger 30 which rides in a channel 31 within head 18. Plunger 30 is normally held out of passageway 22 in a retracted position by means of a spring 32. When it is desired to force plunger 30 into channel 22 25 so as to decrease the size of its discharge opening 19 and reduce the volume of air discharged, said plunger is moved forward through the medium of an annular ring 35 surrounding collar 14. Collar 35 is moved 30 forward by means of a pair of side arms 36 which attach to the opposite sides of ring 35 and extend along opposite sides of cylinder 10 back to a point where they are readily accessible to the operator. When plunger 35 30 is moved forward so as to decrease the discharge opening 19 of passageway 22 the volume of air discharged through said passageway is correspondingly reduced, so that the velocity of the ball, its rotational travel 40 about its axis, and the distance the ball will deviate from its true course, is correspondingly reduced. By means of the above arrangement and construction of parts, the uncertainty of velocity and curve imparted 45 to a ball when manually thrown to deceive a batsman is mechanically imparted to a ball by the use of my invention.

Having thus fully described my said invention, what I desire to secure by Letters 50 Patent, is—

1. The combination with an air gun having an air release port, of a ball projector having revoluble movement about its longitudinal axis, said projector being provided 55 with an air discharge passageway communicating at the longitudinal axis of the projector with the port in the air gun and having its discharge mouth located at one side of the longitudinal axis of said projector.
2. The combination with an air gun having an air release port, of a ball projector having revoluble movement about its longitudinal axis, said projector being provided 60 with an air discharge passageway communicating at the longitudinal axis of the pro-

jector with the port in the air gun and having its discharge mouth located at one side of the longitudinal axis of said projector, and means for rotating said projector about its longitudinal axis. 70

3. The combination with an air gun having an air release port, of a ball projector having revoluble movement about its longitudinal axis, said projector having an air discharge passageway communicating with 75 the port in the air gun, said passageway tapering from its inlet end to its discharge end, and means for holding said projector in operative position.

4. The combination with an air gun having an air release port, of a ball projector having revoluble movement about its longitudinal axis, said projector being provided with an air discharge passageway communicating with the port of the air gun, and 80 means for decreasing the normal area of the mouth of said passageway at the will of the operator.

5. The combination with an air gun having an air release port, of a ball projector 90 having revoluble movement about its longitudinal axis, said projector being provided with an air discharge passageway communicating with the port of the air gun, means for decreasing the normal area of said passageway at the will of the operator, and means for normally holding the preceding 95 means free of said passageway.

6. The combination with an air gun having an air release port, of a ball projector 100 having revoluble movement about its longitudinal axis, said projector being provided with an air discharge passageway communicating with the port of the air gun, means for decreasing the normal area of said passageway at the will of the operator, and means for actuating said preceding means 105 from any position into which the projector is moved throughout its axial travel.

7. The combination with an air gun having an air release port, of a ball projector having revoluble movement about its longitudinal axis, said projector being provided with an air discharge passageway communicating with the port of the air gun, a plunger for decreasing the normal area of the mouth of said passageway at the will of the operator, means for normally holding said plunger free from said passageway, means for rotating said projector about its longitudinal axis, and means for actuating said plunger from any position into which said projector is moved throughout its axial travel. 110

In witness whereof, I have hereunto set 115 my hand and seal at New York city, New York, this 16th day of January, A. D. one thousand nine hundred and nineteen.

BENJAMIN L. BLAIR. [L.S.]
